UNITED STATES PATENT OFFICE

WILLIAM VOLKHARDT, OF STATEN ISLAND, NEW YORK

HYDRANT COCK

Application filed October 8, 1927. Serial No. 224,949.

This invention relates to hydrant cocks and more particularly to means whereby plug cocks can be prevented from jamming and rendered inoperative.

As is well known to those skilled in the art it is frequently necessary to place the cocks of hydrants at considerable distances below the surfaces of the ground where they will not be subjected to freezing temperatures. This is particularly true where hydrants are used in railroad yards, stock yards and the like. It has been the practice to operate these cocks by means of rods adapted to be inserted downwardly into openings or recesses and into engagement with the heads of the valves. Each valve has supported the weight of the rod but the construction has been objectionable because, should a heavy object be dropped on the upper end of the rod or drawn thereover, the rod would be forced downwardly to such an extent as to tightly wedge the valve against its seat. Therefore it frequently has been impossible to turn the valve away from the position in which it has been jammed, any efforts along this line resulting in twisting the head off of the valve and rendering the cock useless. Consequently considerable expense has resulted from the necessity of digging down to the cock and repairing and replacing it.

It is an object of the present invention to provide an attachment for a hydrant cock whereby downward thrust through the operating rod will not cause the valve to bind upon its seat and, consequently, said valve can be rotated readily under any and all conditions.

A further object is to provide an attachment which can be applied readily to hydrant cocks already on the market and can be operated by the usual rod or other means employed for that purpose.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the

scope of what is claimed, without departing from the spirit of the invention.

In the accompanying drawings, the preferred forms of the invention have been shown.

In said drawings,

Figure 1 is an elevation of a hydrant cock located below the surface of the ground and provided with the attachment constituting the present improvement, said attachment being engaged by an operating member extending above the surface of the ground.

Figure 2 is an elevation of a hydrant cock, the attachment thereon being shown in section.

Figure 3 is a side elevation of the attachment.

Figure 4 is an end elevation thereof.

Figure 5 is a section on line 5—5, Figure 3.

Figure 6 is a side elevation of a slightly modified form of the attachment.

Figure 7 is a section on line 7—7, Figure 6.

Referring to the figures by characters of reference 1 designates a hydrant cock having the usual tapered valve 2 provided with a head 3 usually T-shaped. An annular shoulder 4 is provided at the top of the hydrant cock and concentric with the upper portion of the valve 2, this shoulder being found on practically all hydrant cocks in use.

The attachment constituting the present invention comprises a block 5 having a recess 6 extending thereinto of such shape as to receive the head 3 of the valve. This recess is closed at the ends and sides and extending downwardly from the sides of the recess are wings 7 adapted to partly surround the upper portion of the valve 2, the lower ends of these wings being so shaped as to bear against the shoulder 4 with the valve between them. This arrangement has been clearly illustrated in Figure 2. The parts are so proportioned that when the lower ends of the wings 7 are bearing on the shoulder 4 the upper end of the head 3 is spaced from the wall of the recess 6 as shown in Figure 2. If desired an opening 8 can be extended transversely through the block 5 for the reception of a pin. This pin can also be inserted through an opening 10 in the head 3 and when in

position will serve to hold the block firmly to the head.

In practice the hydrant cock 1 is placed in proper position below the surface of the ground and is connected to the pipes 11 and 12 leading to and from the cock respectively. An opening 13 is provided above the cock for the reception of an operating rod 14 having any suitable means, such as an arm 15, at its upper or exposed end whereby it can be rotated readily. The lower end of the rod has a fork 16 designed to straddle the block 5. Thus it will be seen that when the rod 14 is rotated the block 5 will also be rotated and the valve 2 will be moved to open or closed position. It is the practice to leave the operating rod in engagement with the valve. As before explained, however, should a heavy object be dropped on the upper end of the rod or a vehicle passed thereover, the result ordinarily would be the downward jamming of the valve against its seat so that said valve can be rotated with difficulty if at all. By providing the attachment constituting the present invention, however, any downward thrust through the rod 14 will be received by the block 5 and this block, in turn, will transmit the thrust to shoulder 4 so that no driving action will be exerted through the valve. Consequently the valve can rotate freely when the rod 14 is rotated.

If preferred the block can be so constructed as to be engaged and actuated by a threaded rod. A block of this type has been illustrated in Figures 6 and 7. This modified block 17 has a socket member 18 projecting therefrom and internally screw threaded as shown at 19. Thus the threaded end of the rod can be screwed into the socket and will be held in engagement therewith. In other respects the construction of this form of attachment is the same as that of the one already described.

45 What is claimed is:

The combination with a hydrant cock having an elongated head extending from the valve thereof and an annular shoulder concentric with the valve, of a flat, elongated recessed block having apertured sides and closed ends and having opposed arcuate wings forming a reduced portion, said wings being extended from the sides of the recess in the block and separated by a longitudinal slot for the reception of the head of the valve insertable between the wings and into the recess, said slot extending in the direction of the length of the valve head and the width of the slot being slightly greater than the thickness of the valve head, said wings providing relatively large bearing surfaces extending throughout the length thereof for sliding engagement with the annular shoulder, and means extending through the recessed portion of the block for securing the

block to the head to prevent relative displacement thereof, the elongated flat portion of said block constituting means for engagement by the forked end of a valve actuating member and for supporting the weight of said member thereby to transmit thrust from said member to the annular shoulder.

In testimony that I claim the foregoing as my own, I have hereto affixed my signature.

WILLIAM VOLKHARDT.
